UNITED STATES PATENT OFFICE.

HERMANN LEMP, OF ERIE, PENNSYLVANIA, ASSIGNOR TO GENERAL ELECTRIC COMPANY, A CORPORATION OF NEW YORK.

PULVERIZER FOR OIL-ENGINES.

1,069,341.

Specification of Letters Patent.

Patented Aug. 5, 1913.

Application filed October 11, 1912. Serial No. 725,111.

To all whom it may concern:

Be it known that I, HERMANN LEMP, a citizen of the United States, residing at Erie, county of Erie, State of Pennsylvania, have invented certain new and useful Improvements in Pulverizers for Oil-Engines, of which the following is a specification.

The present invention relates to so-called pulverizers for internal combustion oil engines and especially to those of the constant pressure type. These pulverizers must be so constructed that they will inject fuel, such as crude oil for example, into the combustion space of the cylinder in a finely divided state. Another and fundamental requirement of such a device is that it will, when the needle valve is opened to admit the blast air to the combustion space, discharge the fuel contained therein as completely as possible, said fuel having been delivered under pressure to the chamber, well or pocket in the pulverizer during the closed period of the needle valve by a measuring device, such as a pump for example. This latter feature is of the utmost importance because if even a small amount of fuel is left in the pulverizer it will at some succeeding opening of the needle valve pass into the combustion space together with the measured quantity of fuel, as determined by the governor, and give rise to speed irregularities. In other words, there will be too little fuel delivered at one time for a given position of the governing mechanism, and at other times too much. This is especially noticeable at light loads because the said small amount bears a greater percentage ratio to the total amount than at greater loads.

In certain pulverizers with which I am acquainted the fuel is fed into a vertically disposed chamber at its lowest point and all the fuel above a certain level or dam is swept out by the blast air when the needle valve is opened. Such pulverizers while generally operating satisfactorily when occupying vertical positions are defective or inoperative when placed horizontally—(as for example, in a vertical engine of the opposed piston type): chiefly because the fuel collects at one side of the well or chamber and cannot be fully cleaned out with each opening of the needle valve. In such an engine it is impossible to place the pulverizer vertically without making a sacrifice in economy on

the one hand, or simplicity of construction 55 on the other, or both.

The object of my invention is to provide an improved pulverizer for use in a horizontal position which meets all the fundamental requirements specified and which is free 60 from the objections above noted.

For consideration of what I believe to be novel in my invention, attention is directed to the accompanying description and the 65 claims appended thereto.

In the accompanying drawing, which is illustrative of my invention, Figure 1 is a view in end elevation of a constant pressure engine having oppositely moving pistons and equipped with my improved pulverizer; 70 Fig. 2 is a longitudinal section of the pulverizer; Fig. 3 is a cross section taken on line 3-3 of Fig. 2; Fig. 4 is an axial section of a slightly modified pulverizer; Fig. 5 is a cross section taken on line 5-5 of Fig. 75 4; Fig. 6 is a perspective diagrammatic view illustrating the well, pocket or fuel trap formed in the fuel chamber, and Fig. 7 is a detail view showing one end of the plug shown in Fig. 2.

1 indicates the base of the engine, and 2 the vertical cylinder thereof.

3 and 4 indicates respectively the upper and lower pistons. Between the pistons is formed a combustion chamber 5 to which 85 fuel is admitted from the pulverizer 6 under the control of a lever 7 and cam 8, the latter being driven by the main shaft of the engine.

I have shown my improved pulverizer in 90 connection with a vertical engine having oppositely moving pistons. It can, however, be applied to engines in which each cylinder is provided with only a single piston.

Referring to Fig. 2, 9 indicates a horizontally disposed casing that is provided with a beveled end which is seated pressure tight in the cylinder wall. The left hand end of the casing is bored out to receive the discharge device or flame plate 10 which is provided with one or more orifices 11 through which the mixture of fuel and high pressure air is injected into the combustion space. The flame plate may be screw threaded into place, or secured in any other suitable manner. Situated within and snugly fitting the casing is a removable plug or member 12 which is tapered at its left hand

end and is seated pressure tight on a similar face formed on the inside of the casing. The plug is provided with a central bore or opening 13 which is only slightly larger than the valve stem and gradually diverges from about a mid position to its discharge end. This arrangement forms a nozzle in which the air passing through the pulverizer is accelerated and at the same time its pressure is reduced. The object of this arrangement is to insure such a drop in pressure as will permit the fuel to be forced from the fuel chamber through small passages into the bore of the plug or member, as will appear more fully hereinafter. The right hand end of the plug is cut away to form an air chamber 14 between it and the inner wall of the casing; said chamber receiving the blast or high pressure air from the conduit 14a. The chamber communicates by a plurality of relatively small angularly disposed passages 15 with the main bore of the nozzle plug, said passages acting to throttle the air pressure. The plug is held in place by a nut 16 of suitable construction. Passing through the nut and plug, and arranged to engage a beveled seat formed on the casing, is a needle valve 17 which controls the admission of fuel to the engine and is actuated by the lever 7. Between the nut and plug is located a washer or packing 18. Where the needle valve passes through the nut it is provided with a packing 20 of any suitable construction which is compressed by the gland nut 21. As it is sometimes necessary to remove these plugs from the casing for cleaning purposes, said plug is provided with screw threads 22 to receive a suitable withdrawing tool.

Between the plug and the inner wall of the casing is a fuel chamber 24 made in the form of a spiral groove which is closed at its left hand end and is opened at its right hand end to the blast air contained in the chamber 14. The spiral groove may be formed wholly in the casing or wholly in the plug, or partly in the casing and partly in the plug. I prefer, however, to form the groove proper wholly in the plug as shown because of simplicity in manufacture and because the cross sectional area thereof can be more accurately determined. The cross sectional area of this chamber is relatively large. Its size will depend chiefly upon the output of the engine, to which the pulverizer is applied. It should be large enough to receive all of the fuel necessary to drive the engine under full load without said fuel flowing into the air chamber 14. The critical thing is to prevent retention of fuel anywhere in the spiral passage after the needle valve opens. Preferably the size of the groove will be such that all the fuel required at full load will be retained in one turn of the spiral. The air or blast pres-

sure passing through the turns of the spiral pushes the oil delivered by the pump ahead of it in the form of a liquid piston until it reaches the end of the spiral, Fig. 2, or the annular chamber Figs. 4 and 6, and thence forces it directly through the numerous small passages 25 as will be seen later.

In order to convey fuel from its chamber 24 into the diverging portion 13 of the nozzle plug where a pressure less than the pressure in the air chamber 14 exists when the valve 17 is open, a plurality of angularly disposed passages 25 are provided. These passages may be perpendicular to the axis of the valve 17, or they may be slightly inclined to the left as shown so as to increase the suction and mixing or pulverizing effect of the blast of air as it rushes through the nozzle on its way to the engine. The passages 25, if the best effects are to be obtained, should be very small in cross section and numerous. They should bear such a relation to the fuel chamber that the blast air from the chamber 14 can force all the fuel in the pocket in the chamber into the engine at each opening of the valve. By making the cross sectional area of the spiral groove large enough the pressure available for forcing the fuel through these passages will be substantially equal to that contained in the chamber 14. The difference in pressure existing between the entrance and discharge ends of the small radial passages 25 will be governed chiefly by the divergence of the bore or nozzle portion of the plug. By varying this divergence a greater or less difference in pressure can be obtained for a given supply pressure.

Fuel is admitted to the bottom of the pocket in the spiral chamber by the passage 26 that extends longitudinally through the casing and communicates with the inlet 27, the latter being connected to a pump of suitable construction. This pump (not shown) should be capable of delivering oil under a pressure which is substantially greater than the pressure of the air blast in chamber 14. The connection between the oil passage 26 and the spiral supply chamber should be made at the bottom of one of the turns of the spiral and preferably near its closed end so that only a limited amount of pure air will precede the oil supply into the cylinder. This feature is more clearly shown in the diagrammatic illustration Fig. 6, from which it will be seen that the bottom of each turn or bend in the spiral forms a U pocket or well 28, and that the fuel is delivered to the bottom of said bend, well or pocket. This figure also illustrates an annular chamber 29 which forms the closed end of the spiral chamber as illustrated more specifically in Fig. 4.

For the purpose of more clearly illustrating the principle of operation of my inven-

tion I have in Fig. 6 shown the oil passage 24 and the annular chamber 29 as though they were formed of tubing. This figure also illustrates the discharge passages 31.

5 Referring to Fig. 4, the removable plug 12 is made in two parts; that is to say, the main portion surrounded by the spiral groove, and the end portion 30 which is tapered and seated in the casing. Either on 10 the main portion or on the end portion 30, projections are formed between which are small grooves 31, forming passages through which fuel passes from the annular chamber 29 to the diverging portion of the nozzle. 15 These passages should be made small and numerous. For the purpose of illustration I have made them relatively large since otherwise it would be difficult to see them. This arrangement has the advantage that 20 the passages can be readily cleaned if they become plugged up with foreign matter, and also that they can be accurately machined.

It will be seen that the fuel is introduced at the lowest point in one of the turns or 25 bends of the spiral near the discharge end of the plug, and that the fuel is free to flow left and right from the lower portion, said portion forming a trap, pocket or well. It will also be noted that since the right hand 30 end of the spiral is in free communication with the chamber 14 containing the air blast pressure that as the charges of fuel become greater they occupy more space in the supply chamber and work back against said air pressure. Owing to the fact that fuel is introduced into the pocket in the spiral chamber in the manner stated, it follows that when 35 the needle valve is opened all of the fuel contained in said pocket must be forced by the blast air blowing through the chamber 40 into and through the small passages 25 into the enlarged bore of the plug, and therefore, be carried with the blast air through the nozzle 11 into the combustion space.

45 Practical use of the pulverizer shown herein has demonstrated that the fuel will be finely divided as it passes through the pulverizer and will be intimately mixed with the blast air and the compressed air in the cylinder.

50 In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

60 What I claim as new and desire to secure by Letters Patent of the United States, is:—

1. In a fuel pulverizer, the combination of a hollow member having a fuel chamber open at one end and closed at the other 65 which contains a bend intermediate its ends

that forms a trap for fuel supplied thereto, a conduit for supplying fuel to the bottom portion of said bend, small passages leading from said chamber near its closed end to the interior of said member, means for conveying elastic fluid under pressure to the hollow member and to the open end of the chamber for forcing fuel from said bend through the said passages, a valve that controls the action of fluid under pressure on 70 the fuel, and a casing for the member.

2. In a pulverizer, the combination of a casing, a plug fitted therein having an internal bore made in the form of a nozzle to cause a pressure drop between its ends, there being a fuel chamber formed between the casing and the periphery of the plug that is closed at one end and open at the other, and contains a bend intermediate its ends forming a trap, a needle valve which passes through the bore, is separated by a small space from the wall of the bore and engages a seat carried by the casing, a conduit for supplying fuel to said bend at a low point, a plurality of small passages extending 80 from the chamber near its closed end into the enlarged part of said nozzle bore, and a conduit for freely supplying air under pressure to the open end of the fuel chamber and a restricted amount of air to said bore. 85

3. In a pulverizer, the combination of a casing, a plug snugly fitted into the casing which is provided with an external spiral groove forming a fuel chamber that is closed at one end and open at the other and has an internal bore made in the form of a nozzle to cause a pressure drop between its ends, the plug and casing being so related that the casing forms the outer wall of said groove, a valve which passes loosely through the bore and engages a seat carried by the casing, a conduit for supplying fuel to the groove at a point near its closed end, a plurality of small passages extending from the chamber near its closed end into the enlarged part of the bore of the plug, and means for simultaneously admitting blast air to the nozzle and also to the open end of the spiral groove. 100

4. In a fuel pulverizer, the combination of a casing, a plug fitted therein containing a diverging orifice, there being a fuel chamber of spiral form between the two which is closed at one end, one of the turns of said chamber forming a pocket, a conduit for supplying fuel against the blast pressure to the bottom of said pocket from which it is free to flow both right and left, a needle valve that passes through the plug but out of contact therewith, and a plurality of small angularly disposed passages that extend from the portion of the chamber on the discharge side of the pocket into the diverging portion of the orifice in the plug. 105

5. In a fuel pulverizer, the combination 110

of a horizontal casing, a plug fitted therein containing a diverging nozzle orifice, there being a fuel chamber between the casing and plug which is open at one end and terminates in a closed annular portion at the other, said chamber containing a pocket between its ends, a conduit admitting fuel to the bottom of said pocket, a valve, a plurality of angularly disposed passages which convey fuel from the closed annular portion into the enlarged part of the diverging nozzle orifice when the valve is open, and a means for simultaneously supplying air under high pressure to the chamber and orifice. 15

In witness whereof, I have hereunto set my hand this fourth day of October, 1912.

HERMANN LEMP.
